UNITED STATES PATENT OFFICE

116,317

DESIGN FOR A BABY SWING

Albert D. Welsh, Ladue, Mo.

Application May 1, 1939, Serial No. 84,712

Term of patent 14 years

To all whom it may concern:

Be it known that I, Albert D. Welsh, a citizen of the United States, residing at the village of Ladue, St. Louis County, Missouri, have invented a new, original, and ornamental Design for a Baby Swing, of which the following is a specification, reference being had to the accompanying drawings, forming part thereof.

Fig. 1 is a front perspective view of a baby swing, showing my new design; and Fig. 2 is a rear perspective view of the baby swing illustrated in Fig. 1.

I claim:

The ornamental design for a baby swing, as shown.

ALBERT D. WELSH.
